UNITED STATES PATENT OFFICE.

TRUMAN COOKE, OF LOUISVILLE, KENTUCKY.

KNOCKDOWN CRATE.

1,072,826.

Specification of Letters Patent. Patented Sept. 9, 1913.

Application filed November 25, 1912. Serial No. 733,432.

To all whom it may concern:

Be it known that I, TRUMAN COOKE, a citizen of the United States, residing at Louisville, in the county of Jefferson and State of Kentucky, have invented certain new and useful Improvements in Knockdown Crates, of which the following is a specification.

This invention relates to knockdown crates in which the side walls are hinged to a base by horizontal hinges, and two opposite ones of the side walls carry hinged sections which form the top of the crate.

It is the object of the invention to provide a novel arrangement of walls and hinge connections therebetween, whereby the crate can be folded into a small and compact form for convenience in shipment and storage.

The invention also provides for a removable partition whereby the crate when set up can be divided into two compartments when it is desired to separate different varieties of fowls or to prevent the fowls from injuring each other by fighting, etc. This partition also serves as a brace to the crate, preventing it from collapsing when set up.

The invention also has for its object to provide a structure which enables the crate to be set up as a double coop for small chickens.

In the accompanying drawing, forming a part of this specification, Figure 1 is a perspective view of the crate set up ready for use. Fig. 2 is an edge view, partly in section showing the crate folded. Fig. 3 is another edge view of a fragment of the folded crate. Fig. 4 is a fragment of the top portion of the crate, partly broken down. Fig. 5 is a longitudinal section showing

40 the crate set up as a double coop. Fig. 6 is a view of the removable partition showing pins which fit into holes in the floor to retain it in position, the upper edge being secured to the top of crate by twine or wire.

45 In the drawing, 10 denotes the base or floor of the crate. This base is rectangular, and along two opposite edges thereof extend strips 11 forming marginal ledges to which are hinged, horizontally, by means of staples

50 12, walls 13, the latter forming two of the side walls of the crate. The other two side walls 14 of the crate are hinged directly to the corresponding edges of the base by staples 15, the hinge connection being also horizontal. To the top edge of each wall 14 is hinged a section 16, the hinge connection

being made by means of S-shaped hooks 17. The sections 16 form the top of the crate when the latter is set up. The base 10 is also provided with a row of holes 26 midway between and paralleling the walls 14 adapted to receive the pins 27 which project from the under side of the removable partition 28. The side walls and partition as well as the top sections, are made of rectangular frames composed of metal rods or wooden strips covered with wire cloth or netting.

The crate is set up by placing the side walls 13 and 14 in vertical position and unfolding the sections 16 so as to extend across the top of the crate, the length of

said sections being such as to form a complete closure for the top of the crate. The length of the sections 16 is the same as the height of the walls 14, and the walls 13 are

55 so dimensioned that their top edges come flush with the top edges of the walls 14. On the top edge of the walls 13 are dowel pins 18 which enter apertures 19 in the under side of the sections 16, the ends of said sections overlapping the top edges of the walls 13 a sufficient distance so that the dowel pins may enter said apertures. This connection prevents the walls 13 from collapsing

50 when in set-up position. The edges of the sections 16, adjacent to the walls 13, carry loops 20 for fastening said sections down on said walls, which may be done by providing the walls 13 with corresponding

60 loops 21 and passing tie wires through the loops or applying padlocks thereto.

The crate is folded by disconnecting the top sections 16 and swinging the side walls 13 and 14 down into horizontal position.

The side walls 14 are then folded over on top of the base 10 and the sections 16 are folded down on top of said folded side walls. The

70 side walls 13 can now be folded down on top of the folded sections 16, as the height of the ledges 11 corresponds to the combined thickness of the folded parts 14 and 16.

Thus the folded parts 14 and 16 lie between the base 10 and the folded side walls 13. The removable partition 28 can now be secured on top by twine or wire. This manner of folding the crate walls makes a small

75 and compact package and saves space in shipment and storage when the crate is empty.

The crate may also be arranged as a 80 double coop for small chickens as shown in Fig. 5. To do this, the side walls 14 are

swung inward so as to extend at an acute angle to the base 10, and the sections 16 are dropped down so that they also extend at an acute angle to the base, with their free edges 5 in contact therewith. This makes two triangular compartments the end closures of which are made by swinging the walls 13 into erect position across the ends. The walls 13, forming the ends of the compartments, are held up by wire loops 22 passing through the apex of the parts 14 and 16 and engaging said walls 13. The loops 20 seat in recesses 23 in the ledges 11. In order that access may readily be had to the compartments, one of the walls 13 is provided with doors 24.

The preferred embodiment of the invention has been shown, but it will be understood that various minor changes may be 20 made without a departure from the invention as claimed hereinafter.

I claim:

1. A knockdown crate comprising a rectangular base, side walls hinged horizontally 25 to the base along two opposite edges thereof, hinged top sections carried by said walls and forming the top of the crate, ledges on the base along the other opposite edges thereof, and side walls hinged horizontally 30 to the ledges beyond the ends of the first-mentioned side walls, each of the first-mentioned side walls and its hinged top section

being foldable upon themselves and on the base, and the second-mentioned side walls being foldable upon said first-mentioned 35 folded side walls and top sections, and a removable partition wall section which can be temporarily hinged to the free edge of one of the top sections by wire loops substantially as shown and described.

2. A knockdown crate comprising a rectangular base, side walls hinged horizontally to the base along two opposite edges thereof, hinged top sections carried by said walls and forming the top of the crate, ledges on 45 the base along the other opposite edges thereof, and side walls hinged horizontally to the ledges beyond the ends of the first-mentioned side walls, each of the first-mentioned side walls being adjustable to extend 50 at an acute angle to the base, and the top sections being adjustable to extend down from said walls to the base, to form separate compartments, and the second-mentioned side walls being adjustable to extend across 55 the ends of the compartments to close the same.

In testimony whereof I affix my signature in presence of two witnesses.

TRUMAN COOKE.
